UNITED STATES PATENT OFFICE.

LUCIEN B. MARTIN, OF MOUNDSVILLE, WEST VIRGINIA, ASSIGNOR TO
THE FOSTORIA GLASS COMPANY, OF SAME PLACE.

DESIGN FOR A GLASS VESSEL.

SPECIFICATION forming part of Design No. 30,047, dated January 24, 1899.

Application filed December 10, 1898. Serial No. 698,916. Term of patent 3½ years.

To all whom it may concern:

Be it known that I, LUCIEN B. MARTIN, a citizen of the United States, residing at Moundsville, in the county of Marshall, State 5 of West Virginia, have invented and produced a new and original Design for Glass Vessels, of which the following is a specification, reference being had to the accompanying drawings, forming a part of this application.

10 In the drawings, Figure 1 is an elevation of a vessel having my design applied thereto. Fig. 2 is a horizontal section taken on line 2 2 of Fig. 1.

15 My new design is to be applied to glass vessels having flat sides, faces, or flutes A, as shown.

20 I have in the accompanying drawings shown the design as applied to a six-sided vessel with the roccocos, hereinafter referred to, extending downwardly from the beading, and I have shown certain portions of the vessel—to wit,

the top and bottom—in dotted lines, the mouth of the vessel being shown as formed by a line of beading B.

25 The essential features of this design consist of a glass vessel having flat faces, facets, or flutes A and having an ornamentation thereon consisting of roccocos C, projecting from the vessel and extending along the dividing-line between adjacent facets or flutes 30 and connected by raised lines of beading D, extending across the facets.

Having thus described my invention, what I claim, and desire to secure by Letters Patent of the United States, is—

35 The design for a glass vessel herein shown and described.

LUCIEN B. MARTIN.
